(57) **CLAIM**

The ornamental design of an engine enclosure for tracked feller-buncher, as substantially shown and described.

DESCRIPTION

FIG. 1 is a front elevational view of an engine enclosure for tracked feller-buncher, the broken line showing is for illustrative purposes only and forms no part of the claimed design;

FIG. 2 is a back elevational view thereof;

FIG. 3 is a left side elevational view thereof;

FIG. 4 is a right side perspective view thereof;

FIG. 5 is a left side perspective view thereof;

FIG. 6 is a back right perspective view thereof;

FIG. 7 is an enlarged top plan view of the engine enclosure for tracked feller-buncher;

FIG. 8 is a bottom plan view of FIG. 7;

FIG. 9 is a front elevational view of FIG. 7;

FIG. 10 is a back elevational view of FIG. 7;

FIG. 11 is a left side elevational view of FIG. 7; and,

FIG. 12 is a right side elevational view of FIG. 7.

The broken line showing in FIGS. 7-12 is for illustrative purposes only and forms no part of the claimed design.
